EQUIPMENT FOR CARRYING CONTAINERS
AND THE LIKE

Harold O. Davidson, Iron Mountain, Mich.

Application September 15, 1933, Serial No. 689,637

4 Claims. (Cl. 224—25)

The invention relates to equipment to be used for carrying heavy articles, such as standard milk cans and other such containers which cannot be carried by one person without difficulty.

5 An object of the invention is to provide equipment which will enable a man to carry a container such as mentioned with less effort and greater speed, which can be readily released for removing the container or applied to the person 10 with the same ease and facility, and which can be economically manufactured.

Another object of the invention is to provide 15 article carrying equipment for attachment to a person's waist which will hold the load in upright position distributing the weight of the load, part being taken by the person's hips and the remainder by the shoulders, and which will embody novel means for positioning the article on a supporting frame to safeguard against slipping while being 20 carried.

A further object is to provide carrying equipment so constructed as to hold the article carried free from contact with the person at all but one point.

25 In the drawing, which illustrates an embodiment of the device and wherein like reference characters are used to designate like parts—

Figure 1 is a view showing the device of the invention positioning a container on a person's 30 back ready for carrying;

Figure 2 is a side perspective view of the device with the carrying strap and belt in the position they assume when operated;

Figure 3 is a rear perspective of the device 35 shown in Figure 2;

Figure 4 is a sectional view illustrating the association which the base of the container has with the metal supporting frame;

Figure 5 is a detail sectional view taken on line 40 5—5 of Figure 2; and

Figure 6 is a detail sectional view taken on line 6—6 of Figure 4.

The present equipment has been particularly 45 designed for use in combating forest fires where it is necessary to carry water long distances in standard containers, such as 10, and consists in a waistband 11 of any strong and durable material having a buckle 12 secured thereto for adjusting the size of the belt. Attached to the belt 50 at substantially diametrically opposite points are the respective ends of the flexible straps 13 providing the loop 14 at the median portion thereof and being adjustable by reason of the connection 15.

55 Also secured to the waistband 11 is a metal

frame 16 preferably formed of metal tubing and of arcuate shape, with the ends flattened at 17 and secured by rivets or bolts 18 to the band. The ends of the strap 13 are also secured to the band by the rivets or bolts 18, being located between the point and the flattened ends 17 of the frame, as shown in Figure 5.

A yoke 20, formed of a metal rod or tube, bent into a U-shape, has its ends secured to the frame as at 21, Figure 6, the yoke extending upwardly 10 from the frame a distance determined by the height of the container for which the carrier is designed. By passing the loop 14 through the yoke, the flexible strap is associated indirectly 15 with the metal frame.

Also secured to the frame at points within the legs of the yoke are pins 22 which project upwardly from the frame for engaging under the base rim of the container 10, as shown in Figure 4. The pins 22 are purposely located within the 20 legs of the yoke to properly position and hold the container on the frame as shown in Figure 4, whereby the exterior of the rim contacts with the legs of the yoke to thus prevent movement of the container on the frame so that the same will not 25 accidentally slip off while being carried.

To use the device the container to be carried is positioned on the frame 16 with the base of the container engaged by the pins 22 to properly locate the same thereon while loop 14 of the strap 30 is passed around the neck of the container as shown in Figure 1. The strap 13 is then adjusted in length at point 15 so that there is just enough slack to permit the person to get his shoulders through the loops. With this adjustment made the person turns his back to the carrier and slips one arm through the corresponding loop of strap 13 and pulls it up onto his shoulder, then does the same with the other arm and loop. He may then fasten the belt around his waist and 40 walk off with the container securely and comfortably carried on his shoulders and waist, leaving his hands free. As with any heavy pack it is best to first lift the container—with or without the harness attached—to some support about two 45 or three feet above the ground, where it will be easy to get into the shoulder straps.

Although it is not necessary, it has been found desirable as an added precaution in retaining the loop around the neck of the container, to pass 50 the loop through the handle 23. The container is held in upright position on the supporting frame adjacent the person's back as long as the straps are maintained on the person's shoulders. As the yoke 20 is made considerably less in height 55

than that of the container, the loop 14 is pulled downwardly to aid in holding the container in position on its supporting frame. Also the container is held where it will not contact the person, and in a manner which distributes the load between the waist and the shoulders.

The device with container attached can be easily set down by the person carrying it and then the device quickly transferred to another 10 container, or a helper may transfer containers while the device is on the other person's back.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the 15 claims.

20 I claim:

1. Equipment for carrying containers and the like, comprising a belt for attachment to a person's waist, a supporting frame secured to the belt extending rearwardly of the person, a strap 25 having its ends secured to the respective sides of the belt and passing over the person's shoulders so that the median portion of the strap forms a loop adjacent the person's back, said loop engaging the container and assisting in holding the same in upright position on the frame, and a rigid yoke secured to the frame, the loop of said strap being passed under said yoke.

30 2. Equipment for carrying containers and the

like, comprising a supporting frame for attachment to a person's waist to extend rearwardly of said person, a strap secured to the frame, said strap passing over the person's shoulders and providing a loop for engaging the container and holding the same in upright position supported on the frame, and projections on the frame for preventing the base of the container from slipping off the frame while the container is being carried. 5

3. Equipment for carrying containers and the 10 like, comprising a supporting frame for attachment to a person's waist to extend rearwardly of said person, a strap secured to the frame, said strap passing over the person's shoulders and providing a loop for engaging the container and 15 holding the same in upright position supported on the frame, a metal yoke secured to the frame and engaging with the strap between the person's back and shoulders, and projections on the frame for holding the base rim of the container between 20 the yoke and projections.

4. In an article carrier for attachment to a person, a belt having a metal supporting frame of arcuate contour, flexible carrying straps secured to the belt, said straps passing over the 25 shoulders of the person and providing an intermediate loop, said loop passing around the article and holding the article upright when supported on the frame, and means engaging the straps between the loop and shoulders, said means being 30 secured to the frame to aid in holding the article on the frame by drawing the straps taut.

HAROLD O. DAVIDSON.
